(Cl. D7—7)

Fig. 1

To all whom it may concern:

Be it known that I, Paul M. Smith, a citizen of the United States, residing at Portsmouth, in the county of Scioto and State of Ohio, have invented a new, original, and ornamental Design for a Shoe, of which the following is a specification, reference being had to the accompanying drawing, forming a part thereof.

I claim:

The ornamental design for a shoe, substantially as shown.
